UNITED STATES PATENT OFFICE.

HELMAN ABRAMOVITCH, OF LITTLE ROCK, ARKANSAS.

SAFETY ATTACHMENT FOR POCKETS.

1,306,296.

Specification of Letters Patent. Patented June 10, 1919.

Application filed February 19, 1919. Serial No. 277,979.

To all whom it may concern:

Be it known that I, HELMAN ABRAMOVITCH, a citizen of the United States, residing at Little Rock, county of Pulaski, and 5 State of Arkansas, have invented certain new and useful Improvements in Safety Attachments for Pockets, of which the following is a specification, reference being had to the accompanying drawings.

10 This invention relates to certain new and useful improvements in safety attachments for pockets and deals more particularly with that type of devices wherein the inserted article is clipped in position.

15 The main object of the present invention is to prevent as far as possible accidental loss or theft of the inserted article.

Another object of the invention resides in the fact that it will require the use of both 20 hands in order to remove the article from the pocket after it has been secured therein. A still further object of the invention is to associate with the article a part of the securing means which when inserted within 25 the pocket and clipped therein positively prevents its withdrawal in a vertical direction until it has first been moved horizontally to clear the clip.

Another object of the invention resides in 30 the novel arrangement of the pull member to the outside of the pocket whereby the clip to the interior of the pocket may be held to permit the withdrawal of the retained article.

35 While there is described in the following specification and shown in the attached drawings the preferred embodiment of the invention, it is, of course, understood that the present attachment is not so limited, as it may be optionally applied to such articles as watches, pocket books, or, in fact, to any valuable article to which the annular band member can be readily associated. Also the parts as described may be made of various 40 materials, as metal, celluloid, wire, etc., or a combination of any or all of these.

Referring more in detail to the drawings, wherein similar letters of reference indicate like parts throughout:

50 Figure 1 illustrates a perspective view of the plate which is secured to the inner wall of a pocket.

Fig. 2 shows the annular band member associated with a watch stem.

55 Fig. 3 is a plan view partly in section.

Fig. 4 is a side elevation partly in section of the device attached to a pen or pencil.

Fig. 5 is a front elevation.

Fig. 6 is a perspective view of the rear of the plate as shown in Fig. 1.

Fig. 7 is a top plan view, showing two clips arranged on the plate.

Fig. 8 is a perspective view of a slightly modified form of the plate wherein all of the parts are stamped from a single sheet.

Fig. 9 is a further modification of the clip, and Fig. 10 shows the annular member used on the inserted article when such a clip as that shown in Fig. 9 is employed.

In the drawings 1 indicates a garment 70 pocket to the inner wall of which the plate 2 is arranged. This plate 2 may have riveted thereto, as shown in Fig. 1, or stamped therefrom, as in Fig. 8, a spring clip 3 and extending to the opposite side of the plate 75 are stamped out or bent ears 4. These ears 4 are perforated, as at 5, for the purpose hereinafter described. As shown in Figs. 3 and 4, the perforated ears 4 extend through the front wall of the pocket 1 and inserted 80 through the perforations is a bar 6 of a snap pin 7. In order to prevent the unsightly appearance of the ears 4 and also the snap pin 7, a pull member 8 is employed, preferably of leather, which is secured to the 85 bar of the snap pin, as more clearly shown in Fig. 4.

Associated with the article to be secured within the pocket is a band member 10 which is preferably split, as shown at 11, said band 90 being of a sufficient resilient nature to firmly grip the article and prevent relative longitudinal slippage thereof. This band is provided with a flange 12 at each longitudinal end thereof so that the band as a whole presents an annular formation which is readily slipped into the spring-clip 3 with a flange above and one below the clip, as shown in Fig. 4.

As illustrated in Fig. 7, a plurality of clips 100 of varying sizes may be employed if desirable for securing articles of various cross diameters.

The modified form illustrated in Fig. 9 consists in slotting the side walls of the 105 spring clip 3 as at 3' for the purpose of receiving the annular member 10, shown in Fig. 10, which is attached to the article to be secured in position. It will readily be understood that the annular member 10' enters 110

the slotted portions of the spring clip thereby effectively preventing the vertical withdrawal of the article until it has first been moved horizontally to clear the clip.

5 The parts being in their applied positions, a brief description of the manipulation of the device is as follows: The article is inserted within the pocket and is moved forward until the annular band member is 10 snapped into the spring clip with its flanges disposed one above and one below the clip. When it is desired to withdraw the article the operator grasps the pull member with one hand and the inserted article with his 15 other, then, by causing a relative horizontal movement between the parts until the band is clear of the clip, the article may then and then only be withdrawn from the pocket.

Although I have herein shown and described the preferred embodiment of the invention, it is to be understood that various changes and modifications may be made without departing from the spirit and scope 20 of the appended claims.

25 I claim:

1. In a device of the character described, the combination of a spring clip adapted to be permanently secured in position within a pocket, and an annular member arranged 30 on the inserted article and adapted to be secured in the spring clip.

2. In a device of the character described, the combination of a spring clip adapted to be permanently secured in position within a pocket, and a channeled band arranged on 35 the inserted article and adapted to be secured in the spring clip.

3. In a device of the character described, the combination of a spring clip adapted to 40 be permanently secured in position within a pocket, and a member provided with terminal enlargements arranged on the inserted article and adapted to be secured in the spring clip with said enlargements disposed 45 to either side thereof.

4. In a device of the character described, the combination of a spring clip arranged within a pocket, means associated with said 50 clip and extending through the wall of the pocket, and a fastening member connected therewith for securing the clip in position within the pocket, and an annular member arranged on the inserted article and adapted to be secured in the spring clip.

5. In a device of the character described, the combination of a metal plate adapted to 55 be secured to the inner wall of a pocket, said plate being provided with resilient clip arms, and a channel-shaped member associated with the inserted article, said channel-shaped member to be secured between

the resilient clip arms to prevent a vertical withdrawal of the article until the same has first been moved in another direction.

6. In a device of the character described, 65 the combination of a metal plate adapted to be secured to the inner wall of a pocket, said plate being provided with resilient clip arms, and means associated with the inserted article and adapted to be secured between the clip arms to prevent a vertical withdrawal of the article until the same has first been moved in another direction.

7. In a device of the character described comprising a spring clip arranged to the 75 inner side of a pocket, means connected with the clip and extending through the wall of the pocket, and a fastening member connected to the extending end to securely hold the clip in position within the pocket, said 80 fastening member constituting a grip whereby the clip may be positively held to permit the withdrawal of the retained object.

8. In a device of the character described comprising a metal plate arranged within 85 a pocket, said plate having inwardly extending therefrom a spring clip and outwardly therefrom a plurality of perforated ears, said ears adapted to project through the wall of the pocket, and a crossbar inserted 90 through the apertured ears to hold the plate in position within the pocket.

9. In a device of the character described comprising a metal plate arranged within 95 a pocket, said plate having inwardly extending therefrom a spring clip and outwardly therefrom a plurality of perforated ears, said ears adapted to project through the wall of the pocket, and a snap pin having one of its bars inserted through the 100 apertured ears to hold the plate in position within the pocket.

10. In a device of the character described comprising a metal plate arranged within a pocket, said plate having inwardly extending therefrom a spring clip and outwardly therefrom a plurality of perforated ears, said ears adapted to project through the wall of the pocket, a snap pin having one of its bars inserted through the 105 apertured ears to hold the plate in position within the pocket, and a pull member associated with the other bar of said snap pin whereby the clip may be held to permit the withdrawal of the retained article.

In testimony whereof I affix my signature in presence of two witnesses.

HELMAN ABRAMOVITCH.
